UNITED STATES PATENT OFFICE.

JOSEPH CONLEY, OF ANADARKO, OKLAHOMA.

ARMY-KITCHEN.

1,272,382.

Specification of Letters Patent. Patented July 16, 1918.

Application filed December 5, 1917. Serial No. 205,593.

To all whom it may concern:

Be it known that I, JOSEPH CONLEY, a citizen of the United States, residing at Anadarko, in the county of Caddo and State of Oklahoma, have invented certain new and useful Improvements in Army-Kitchens, of which the following is a specification.

This invention relates to ovens, and more particularly to portable ovens particularly adapted for army field use.

One of the objects of the present invention is to provide a simple and practical oven of the above general character which may be conveniently transported and removed from the transporting means and set up if so desired upon a stationary base. A further object is to provide an oven of the above general character capable of conveniently and efficiently permitting all of the services desired in connection with an army commissary of an army camp. A further object is to provide an exceedingly practical oven of the above type which may be conveniently regulated and adjusted for permitting any desired degree of heat to come in contact with the material to be treated. A further object is to provide an oven having the maximum capacity and efficiency at a minimum expense.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof, all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings like characters of reference denote corresponding parts throughout all the views, in which—

Figure 1 is a perspective view showing the device removed from the transport;

Fig. 2 is a longitudinal sectional view of the oven;

Fig. 3 is an end sectional view of the oven on its transport;

Fig. 4 is an end view of the device in use; Fig. 5 is a detail view of the burner;

Fig. 6 shows how the oven may be stored.

Referring now to the drawings in detail 5 denotes a motor truck of general construction having a platform 6 upon which the oven 7 is removably mounted.

Suitable platforms 8 and 10 are mounted at the ends and sides of the oven whereby they may be conveniently swung down into 65 horizontal position to permit the cooks to move freely about the oven in preparing meals. Steps 11 permit convenient access to these platforms as may be necessary. When the oven is not in use the platforms are 70 swung upwardly as indicated in Fig. 3, thus more or less inclosing the oven and permitting the vehicle to move freely without undue lateral obstructions.

Referring more particularly to Figs. 2 75 and 3 where the oven is shown in section, a suitable base 12 constitutes an ash-pit above which is a deck including a grate 13 forming a base to the fire box 14 supporting an oil burner 15 as shown in Fig. 5 or fuel as desired, which may be admitted through a door 16 provided with a damper 17. The products of combustion may be made to pass through openings 18 and 20 into a stack 21

80 by opening dampers 22 and 23 respectively. If the damper 23 is closed the products of combustion then follow the arrows as indicated to the opposite end of the oven where they pass through opening 24 which may be closed by damper 25 thence back across the 90 top of the oven and out through opening 26 to the stack if not closed by damper 27. These dampers may be opened entirely or to any desired degree as may be necessary, ac-

95 cording to the degree of heat desired. The dampers 22 and 25 are supported by decks or tiers 28 and 30, and additional decks or tiers may be provided if so desired. It is to be noted that the oven is made up of sections both horizontally and vertically and may 100 be enlarged to any desired degree as may be necessary.

The top 31 of the oven is provided with openings normally closed by lids 32, as is customary with the usual type of cooking stove. The dampers 22 and 25 not only perform the function for which they are particularly designed but also constitute deflectors for conducting the direct heat currents away from receptacles 33 containing 110

the food to be cooked, thereby preventing burning or warping of such containers. It will be seen that corrugated bottoms are provided to distribute the heat and prevent 5 burning.

By reference to Fig. 2 it will be noted that the deck 28 is provided with an auxiliary oven 34 which may be moved bodily transversely of the oven through openings at the 10 side normally closed by door 35. This is particularly adapted for use in baking pastry or meats where direct contact with the heat currents is to be avoided.

By reference to Fig. 1 it will be noted that 15 the side of the oven is provided with a plurality of doors 36 permitting access to the interior. As the upper deck is particularly designed for either heating water or evaporating liquids, the relatively long containers 20 33 may be removed more conveniently from the oven through these doors. Suitable damper actuating means 37 are provided wherever necessary.

It is believed that the construction of the 25 present device will be clear to those skilled in the art from the above description, and a brief statement of the operation thereof is as follows:

On starting a fire unless the oil burner is 30 used the dampers 22 and 23 are partially opened to form a direct passage-way to the stack 21. The fire is lighted above the grate 13 through the door 16 and after the fire has been well started the damper 23 may be 35 closed and the dampers 22-25 and 27 opened the desired degree to permit the proper amount of heat to pass back and forth over the containers. If practically no 40 heat at all is desired a damper 40 is opened to provide a passage way 41 which permits the products of combustion to pass downwardly through the grate 13 over the ash-pit and thence up the stack 21. This arrangement of dampers may be used when 45 starting a fire if so desired. When it is necessary to remove the ashes or waste from the ash-pit 12 a door 42 is removed after which they may be conveniently raked out at the forward end.

Copies of this patent may be obtained for five cents each, by addressing the "Commissioner of Patents, Washington, D. C."

Fig. 6 indicates how the platforms may be 50 used as a shelter for the oven and supplies when in camp.

It is thus seen that the present invention provides a simple and practical oven particularly adapted for camp use, and is believed to accomplish, among others, all of the objects and advantages herein set forth.

I realize that considerable variation is possible in the details of construction and arrangement of parts without departing 60 from the spirit of my invention, and I therefore do not intend to limit myself to the specific form shown and described.

Having thus described my invention what I claim as new and desire to secure by Let- 65 ters Patent is:

1. In an oven of the character described in combination, an outer casing provided with a plurality of horizontal decks arranged one above the other, the space above the bottom deck constituting an ash-pit, and the space above the second deck constituting a combustion chamber, a stack at one end of the casing and dampers associated with the space above each deck and the stack as well 75 as between the spaces above the decks whereby the products of combustion may pass in any desired quantity either directly to the stack through the ash pit or back and forth over one or more of the decks. 80

2. In an oven of the character described in combination, a casing, a series of superposed decks within said casing, a combustion chamber, a flue below said combustion chamber, a stack, and dampers associated 85 with said flue and stack whereby the products of combustion may be caused to pass from the combustion chamber into the flue and thence to the stack, or back and forth through one or more of the decks and 90 to the stack.

In testimony whereof I affix my signature in presence of two witnesses.

JOSEPH CONLEY.

Witnesses:

K. E. KLEIN,
F. L. BROWNE.
